ROCK DRILL FRONT END

John C. Curtis, Garfield Heights, Ohio, assignor
to The Cleveland Rock Drill Company, Cleve-
land, Ohio, a corporation of Ohio

Application September 6, 1935, Serial No. 39,465

7 Claims. (Cl. 121—32)

This invention pertains broadly to rock drills, but more particularly to the front end construction of rock drills of the percussive type.

One object of this invention is to produce a 5 rock drill front end of simple construction, which is strong, durable and efficient.

Another object of this invention is to produce a rock drill front end especially designed to operatively receive the shank of a broaching steel.

10 Another object of this invention is to produce a rock drill front end with readily renewable bearing means adapted to slidably receive the shank of a tool implement.

Other objects more or less ancillary to the foregoing reside in the specific construction and arrangement of the elements peculiar to this structure, as will become apparent from a more complete examination of this specification.

Referring to the drawing which illustrates the 20 invention:

Fig. 1 is an elevational view partly in section of a rock drill front end having the invention applied thereto.

Fig. 2 is a cross sectional view taken through a 25 plane indicated by line 2—2 of Fig. 1.

Fig. 3 is a view similar to Fig. 2 but taken through a plane indicated by line 3—3 of Fig. 1.

Fig. 4 is also a cross sectional view taken 30 through a plane indicated by line 4—4 in Fig. 1. Fig. 5 is an end view of the rock drill front end illustrating the retainer in the position shown in Fig. 1.

In this illustrative construction, 10 represents a rock drill front housing having its upper end 35 adequately machined to receive the front end of a cylindrical bushing 11 depending from the cylinder 12 of the rock drill, within which is reciprocably mounted a piston 13 having the front end thereof guided within a sleeve 14 rotatably 40 mounted within the bushing 11.

Leading from the front end of the housing 10 into the interior thereof, there is an aperture formed of three flat bottom bores 15, 16, and 17. The bore 16 is disposed in coaxial alignment with 45 the longitudinal center axis of the housing, while the bores 15 and 17 are located on the side thereof in parallel alignment therewith to form an aperture of elongated cross section. Toward its end, the bore 16 is circularly enlarged as at 18 to afford the communication of the bores 15 and 17 with the front end of the hammer piston 13. Each bore 15 and 17 has an elongated element or 50 guide 19 mounted therein, with one end engaging the flat bottom of the bore, while the other end 55 thereof is substantially flush with the front end

of the housing 10. The guides 19 are of crescent shape cross section, with the external wall thereof shaped to cooperate with the corresponding inner wall of the bores within which they are disposed, for maintaining the guides against lateral movement. The inner wall of the guides 19 is arcuated as at 20, and provided with a U-shaped slot 21 extending the full length thereof. The guides 19 are maintained within their respective bore by a plate 22 engaging the front end of the 10 housing 10. This plate together with the front housing 10 is secured to the rock drill cylinder 12 by a pair of bolts 23 extending therethrough to receive cooperating nuts 24. The plate 22 is provided with a protuberance or key 25 extending 15 upwardly therefrom between the guides 19, which have their front end machined as at 26 to snugly receive the same, thus positioning the U-shaped slot 21 of the guides in diametrical opposition and preventing the rotation of the guides with respect 20 to the housing 10. The plate 22 is formed with a bore 27 disposed in coaxial alignment with the bore 16, and U-shaped slots 28 extending away from the bore 27 in coaxial alignment with the slot 21 of the guides 19.

Adjacent each bolt 23, the plate 22 is provided with a transversally apertured boss 29 having a bolt 30 extending therethrough to pivotally receive a pair of links 31. One pair of links has pivotally secured thereto by a bolt 32 a fork 30 shaped member 33 having each side arm thereof provided with a hook 34. Similarly secured to the end of the other pair of links by a bolt 35, there is a fork shaped member 36 having its side arms equipped with laterally projecting trunnion 35 37 adapted to pivotally receive the corresponding hook of the member 33. Formed through the member 36, there is a bore 38 corresponding to the bore 27 of the plate 22 and located in coaxial alignment therewith. The bore 38 is also provided 40 with U-shaped slots 39 extending therefrom into the members 33 and 36 in diametrical opposition to each other. The upper portion of the end walls 40 of the slots 39 is perpendicular to the plate 22, while the lower portion thereof is inclined as at 41.

Slidably mounted within the slot of the guides 19, there is the shank 42 of a tool implement. This shank is of rectangular cross section with the side walls thereof longer than its end walls. 50 The shank also extends through the opening formed in the plate 22 and members 33 and 36 depending therefrom. The free end of the shank is circularly enlarged as at 43 to provide an adequate end surface adapted to receive the blows 55

of the hammer piston 13. In practice it has been found that when the free end of the shank is not enlarged as shown in the drawing, the 5 blows imparted thereon by the hammer piston cause the middle portion of the side walls of the shank to flare or expand outwardly. The bore 16 provided between the guides 19, together with the arcuated inner wall 20 of the latter, afford sufficient clearance for a free passage of the enlargement 43, which may be purposely provided at the 10 end of the shank, or may be the result of the blows imparted thereto by the hammer piston. The plate 22 being provided with a bore similar to the bore 16, will also permit the free passage 15 of the end of the shank irrespective of the enlargement formed therein.

Referring to the mechanism depending from the plate 22, it will be understood that upon downward pressure exerted on the member 33, the upper edge of the end walls 40 of the slots 39 will be moved inwardly in clamping engagement with the shank, thus retaining the latter within the housing 10. The enlargement 43 formed at the end 25 of the shank is free to pass through the bore 38 in the tool retaining device, thus permitting the shank to be introduced into or removed from the housing 10 without disconnecting the members 33 and 36.

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

I claim:

1. In a front end construction for rock drills, 40 a front housing formed with an aperture, a tool implement having a shank slidably guided within said aperture, said shank and aperture being of rectangular cross section with the side walls thereof longer than its end walls, the middle portion of the side walls of said shank toward the 45 free end thereof being flared to form an enlarged end surface, and a passage between the marginal edge of the side walls of said aperture affording the free introduction or removal of said shank 50 into or from said aperture irrespective of the flared portion of said shank.

2. In a front end construction for rock drills, a front housing, guideways within said housing, a tool implement having a shank of rectangular 55 cross section slidably guided within said guideways, and an enlargement at the free end of said shank, said guideways formed and disposed in a manner affording the free slidable movement of said shank therein irrespective of said enlargement.

60

3. In a front end construction for rock drills, a front housing, guideways within said housing, a tool implement having a shank slidably guided within said guideways, an enlargement formed on said shank extending to the free end thereof to cause the free end area of said shank to be greater than the normal cross sectional area thereof, and a clearance between said guideways affording the free slidable movement of said shank irrespective of said enlargement. 5

4. In a front end construction for rock drills, the combination with a front housing having an aperture formed therein, of a tool implement having a shank slidably guided within said aperture, an enlargement formed at the free end of said shank, a tool implement retaining device carried by said housing movable in operative or inoperative position for preventing or permitting the removal of said shank from said housing, and a passage within said device arranged and disposed in a manner whereby the enlargement formed at the end of said shank remains in spaced relation with said device irrespective of the position of the latter. 10

5. In a front end construction for rock drills, 25 a front housing having a duality of bores leading from its front end into the interior thereof, said bores being diametrically opposed to each other in parallel alignment with the longitudinal center axis of said housing, an element within each of 30 said bores having a guideway formed therein, a tool implement having a shank slidably guided within the guideway of said elements, and means for detachably securing said elements in said housing against movement relative thereto. 35

6. In a front end construction for rock drills, a front housing, an opening leading from the front end into the interior of said housing in coaxial alignment with the longitudinal center axis thereof, a duality of elements within said opening, 40 the inner wall of said opening and the external wall of said element being formed for cooperative engagement in a manner whereby said elements are maintained in parallel spaced relation with each other, a guideway formed within each of 45 said elements in opposition to each other, a tool implement having a shank slidably guided within said guideways, and means for detachably securing said elements in said housing against 50 movement relative thereto.

7. In a front end construction for rock drills, a front housing having a duality of bores leading from its front end into the interior thereof, a removable guideway within each of said bores, a 55 tool implement slidably guided within said guideways, and means for detachably locking said guideways in said housing against movement relative thereto.

JOHN C. CURTIS. 60
